UNITED STATES PATENT OFFICE.

GARNET C. BROWN, OF DAYTON, OHIO, ASSIGNOR TO THE WILLYS-OVERLAND COMPANY, OF TOLEDO, OHIO, A CORPORATION OF OHIO.

LUBRICATING SYSTEM.

1,427,190.

Specification of Letters Patent. Patented Aug. 29, 1922.

Application filed February 27, 1919. Serial No. 278,574.

To all whom it may concern:

Be it known that I, GARNET C. BROWN, residing at Dayton, Montgomery County, State of Ohio, have invented certain new and useful Improvements in Lubricating Systems, of which I declare the following to be a full, clear, and exact description.

This invention relates to an improved lubricating system, which may be employed in connection with internal combustion engines for feeding oil to the bearing shafts carrying the mechanism for operating the valves of the engines.

One object of the invention is to provide a lubricating system whereby the various bearings may be lubricated from a single oil supply pipe.

A further object of the invention is to provide a lubricating system wherein a constant and uniform supply of oil is at all times applied to the bearing surfaces.

A further object of the invention is to provide a lubricating system which is of simple construction and efficient in operation.

Further objects of the invention relate to economies of manufacture and details of construction as will hereinafter appear from the detailed description to follow.

The objects of the invention are accomplished in one instance by the devices and means described in the following specification, but it is evident that the same may be varied widely without departing from the scope of the invention, as pointed out in the appended claims.

A structure constituting one embodiment of the invention, which may be the preferred, is illustrated in the accompanying drawings forming a part hereof, in which:

Fig. I is a vertical-sectional view of an internal combustion engine of the V-type, taken substantially on the line I—I of Fig. II, and illustrating the position of the various operating parts of the mechanism.

Fig. II is a top-plan view, partially in section, taken along the line II—II of Fig. I, illustrating the relative position of the various rocking arms with respect to the cam shaft, and showing a portion of the lubricating system.

Fig. III is a vertical-sectional view taken along the line III—III of Fig. II, and illustrating the manner of feed-oil from the hollow cam shaft to the several bearings.

Fig. IV is a vertical-sectional view taken along the line IV—IV of Fig. II.

Fig. V is a vertical-sectional view taken along the line V—V of Fig. II.

In the drawings, similar reference characters refer to corresponding parts throughout the several views, and the sectional views are taken looking in the direction of the small arrows at the ends of the section lines.

Referring to the drawing, the engine comprises cylinders 10 arranged in two rows or series, the cylinders of each row being oppositely inclined with respect to the corresponding cylinders of the opposite row. Cylinder heads 11 are positioned above the cylinders of each row and secured thereto in any well known manner.

A top casing section 12 is adapted to extend across the head casings 13 and carries the cam shaft, and the various rocking arms actuated thereby for operating the valves. The top casing section is firmly secured to the cylinder head casings in any suitable manner. A removable cover 13 is firmly secured to the upper portion of the top casing section, and is capable of removal for the purpose of pro-

viding a means of ready access to the cam shaft and the various elements operated thereby. An outer wall 14 surrounds the several cylinders and is spaced therefrom to provide a water jacket space about the cylinders. The head casings carry the usual spark plugs 16, and are provided with the usual intake passages 17 and exhaust passages 18, all communicating with the interior of the cylinders. Each of the said intake and exhaust passages are provided, with valve seats properly arranged therein at the point where each of the several passages communicate with the interior of the corresponding cylinder. Positioned within the

several intake passages in such a manner as to properly seat upon the valve seats 19, and carried by the casing, are intake valves 20, each of which is provided with a valve stem 21 extending upwardly therefrom and terminating in a head portion 22. In a similar manner, each of the exhaust passages is provided with an exhaust valve 23 adapted to seat in the proper manner upon the corresponding valve seat 19, and provided with an upwardly extending valve stem 24 terminating in a head 25. The exhaust pas-

sages 18 from the several cylinders comprising one series or row, communicates with the exhaust manifold 26.

The lower portion of the top casing section 12, and the upper portion of the cyl-

inder head casings are so constructed as when properly assembled to form a firm support for the top casing, and provide means for firmly securing the parts together. A 5 hollow cam shaft 27 extends in a direction substantially parallel with the engine crank shaft (not shown), and is adapted to be rotated from the crank shaft in any suitable manner so as to give it a speed of rotation 10 proportionate to that of the crank shaft. The hollow cam shaft 27 carries a plurality of cam elements 28 firmly secured thereto, the said cam shaft being suitably supported in bearings 29 formed in the top casing section 12. The top casing section 12 is provided with portions 30 forming bearings for a pair of hollow shafts 31, which extend in a direction substantially parallel to each other and to the cam shaft, and are positioned 15 upon opposite sides of the cam shaft and in substantially the same horizontal plane therewith. The shafts 31 are adapted to provide bearings for firmly supporting a plurality of upper and lower rocker arms 25 32 and 33 respectively. The rocker arms 32 and 33 are of similar construction and extend in opposite direction from the cam shaft for a purpose which will be hereinafter described. The top casing section is also 30 provided with a plurality of bearings 34 for suitably supporting a plurality of hollow shafts 35, which also extend in a direction parallel to the direction of the cam shaft and upon opposite sides thereof, they being positioned 35 outwardly with respect to the shafts 31, and each of the said hollow shafts lying substantially in the plane determined by the longitudinal axes of the cylinders comprising one row or series. 40 Each cylinder is provided with a pair of exhaust valves 23 having stems 24 extending upwardly through the head casing, and adapted to slide in bearing sleeves 37 positioned within the head casing. A coiled 45 spring 38 surrounds the upper portion of each of the valve stems 24, and bears at its lower end against a cup-shaped washer 39 carried by the valve stem. In a similar manner each of the cylinders is provided with 50 a single intake valve 20 having a valve stem 21 extending upwardly through the head casing and slidably mounted in a bearing sleeve 40 secured therein. Each of the several valve stems 21 is surrounded by a coil 55 compression spring 42, the lower end of which is adapted to bear against a portion of the head casing, the upper end bearing against the under surface of a cup-shaped washer 43 secured to the upper end of the 60 valve stem. 65 Revolvably mounted upon each of the hollow shafts 35 at a point directly above each of the cylinders 10 is a sleeve 44, provided with a pair of integral arms 45 extending therefrom in a direction towards the cam shaft, and positioned in such a manner that the inner ends of the arms 45 extend over and are adapted to rest upon the heads 25 of the two valve stems 24, with which the exhaust valve 23 of each cylinder are provided. Each of the sleeves 44 is provided with an enlarged portion 49 substantially centrally thereof which serves as a housing for a sleeve 46 adapted to be positioned therein, and revolvably mounted upon the 70 hollow shaft 35. Each of the sleeves 46 is provided with a pair of arms 47 and 48, adapted to extend in opposite directions therefrom, the said arms 48 being designed to extend outwardly from the shaft 35 in 75 such a manner that its outer end will overlie and contact with the head 22 of the valve stem 21 carried by the intake valve 20 of each cylinder. The enlarged portion 49 of the sleeve 44 is provided with diametrically opposite openings 50 for the reception of the arms 47 and 48, said openings being of such size as to permit a suitable rotative movement of the sleeve 46 and the arms 47 and 48 carried thereby with respect to the 80 sleeve 44. 85 Each of the upper and lower rocker arms 32 and 33 respectively are provided with bearing portions 52 positioned near the central portion of each of the rocker arms, and adapted to be rotatably mounted upon one of the shafts 31 in such a manner as to permit the rocker arms to oscillate thereon upon rotation of the cam shaft. Each of the upper rocker arms 32 is positioned in such a 100 manner that its inner end overlies the cam shaft and has secured thereto a roller 53 adapted to contact with one of the cam elements carried by the cam shaft in such a manner as to oscillate the rocker arm upon 105 rotation of the cam shaft. In a similar manner each of the lower rocker arms 33 is rotatably mounted upon the corresponding shaft 31, and has its inner end extending to a position beneath the cam shaft, the said inner end of each rocker arm 33 being provided with a roller 54 adapted to contact with and be actuated by one of the cam elements carried by the cam shaft for the purpose of 110 communicating oscillatory movement to the 115 lower rocker arm. The outer end of each of the upper rocker arms 32 is adapted to overlie and rest upon the inner end of one of the arms 45 carried by the sleeve 44, in such a manner that when the inner end of the 120 rocker arm 32 is raised by one of the cam elements, the outer end of the rocker arm will be depressed, thus forcing downwardly the arms 45 and the corresponding valve stems 24 secured to the exhaust valve 23 for the 125 purpose of permitting exhaust of the combustion gases from the cylinders. The outer end of each of the lower rocker arms 33 is positioned beneath and adapted to contact with the end of the inwardly extending arm 130

47 secured to the sleeve 46. When each of the lower rocker arms is oscillated by the cam elements 28 of the cam shaft co-operating with the roller 54 upon the inner end of the rocker arm, the outer end of said arm will be correspondingly raised whereby the sleeve 46 will be oscillated and the arm 48 will press upon the head 22 of the valve stem carried by the inlet valve of the cylinder to open the valve and permit fuel to be drawn into the cylinders.

The hollow cam shaft 27, and the hollow bearing shafts 31 and 35 are so disposed as to be substantially parallel to each other, and are each supported in a plurality of bearings carried by the top casing section as shown and described. The open end of the hollow shafts 35 are covered by caps 55 secured to the casing in such a manner as to securely close the ends of those tubes and prevent the leakage of the oil therefrom. The ends of the hollow bearing shafts 31 are provided with caps 56 constructed in a manner similar to that of the caps 55 previously described, and adapted to close the ends of the hollow bearing shafts to prevent the leakage of oil therefrom. The central opening in the hollow cam shaft may be constructed in such a manner as to terminate short of the end of the shaft at one end, as shown in Fig. III and the opposite end of the cam shaft may be closed in any desired manner to prevent the leakage of oil therefrom. A supplemental housing 57 may be secured to the top casing section at a point near one end of the cam shaft for the purpose of inclosing operating mechanism including a crank arm 58, secured to the cam shaft and adapted to operate an air pump 59, which may be used for the purpose of operating a force feed mechanism designed to feed the liquid fuel to the engine cylinders. A conduit 60 is formed in the top casing section extending in a direction substantially at right angles to the several hollow shafts, and adapted to communicate with the interior of each hollow shaft in such a manner as to feed oil thereto. If desired, a similar conduit may be formed in the opposite end of the top casing section (not shown) and communicating with the interior portion of each of the hollow shafts, so as to serve as a means for securing a continuous circulation of the lubricating fluid through the hollow shafts. It will be noted upon reference to Fig. I that the cam shaft 27 is located slightly above the horizontal plane of the bearing shafts 31, while the bearing shafts 31 are in turn located somewhat above the horizontal plane of the bearing shafts 35. By reason of this construction the conduit 60 which is preferably a straight passage formed in the casing, is located slightly beneath the cam shaft 27, and the hollow shafts 31, while it extends somewhat above the level of the hollow shafts 35. Each of the hollow shafts 35 is provided with a plurality of radial openings 62 formed therein near the extremity of the shaft in such a manner as to communicate with the openings 61 through a circular passage 61' and provide means for admitting oil from the conduit 60 to the interior of each of the hollow shafts 35. In a similar manner, the conduit 60 is provided with openings 63 formed therein at points near the extremity of each of the hollow bearing shafts 31, and the hollow bearing shafts 31 are each provided with a plurality of radial openings 64 formed therein, which are adapted to communicate with the opening 63 through a circular groove 65 communicating with the openings 63 and 64 for the purpose of admitting oil to the interior of the hollow shaft 31 from the conduit 60. The constantly rotating cam shaft 27 is provided with a plurality of radial openings 66 so positioned as to communicate with an opening 67 extending from the conduit in such a manner as to admit oil to the interior of the cam shaft upon rotation of the same. Each of the hollow bearing shafts 35 is provided with radial openings 68 positioned in such a manner throughout its length as to properly supply oil to the bearing sleeves 44 and 46 mounted thereon, for the purpose of providing suitable lubrication for the same. In a similar manner, the bearing shafts 31 are provided with a plurality of radial openings 69 positioned in such a manner as to properly lubricate the bearing portions 52 of the rocking arms 32 and 33 carried by said shaft 31. The cam shaft 27 is also provided with a plurality of radial openings 70 positioned intermediate the bearings 29 within which the cam shaft is revolvably mounted so as to properly furnish lubrication for the cam shaft within the bearings. An oil supply pipe 71 communicates with the conduit 60, which is adapted to communicate with an oil reservoir (not shown) for the purpose of supplying oil to the lubricating system.

It will be readily apparent from the above description that the construction shown and described provides a convenient and efficient means for furnishing lubrication to the several bearings of the cam operating mechanism of an engine of this type, whereby a constant and uniform supply of lubrication is furnished to the various bearing surfaces at all times. In the operation of this device oil is supplied to the conduit 60 through the oil supply pipe 71 from the main oil supply reservoir, and is fed from the conduit to the interior of the cam shaft and the various hollow bearing shaft in a manner which will be obvious from the previous description. The supply of oil carried by the hollow cam shaft and the various hollow bearing shafts will be suit-

ably supplied to the bearing surfaces through the radiating openings formed in these shafts in such a manner as to properly lubricate the bearing surfaces.

5. By the use of the structure illustrated herewith, the necessity for employing a plurality of grease cups or other separate lubricating means for each shaft or each bearing is dispensed with, and the cost of
 10 construction as well as the care necessary to be exercised in keeping the parts supplied with lubrication is considerably lessened. By providing the circular passages 61' and 65, a free passage is maintained at all times
 15 for feeding lubricant to the interior of the hollow shafts 35 and 31, which shafts are not rotatable under ordinary conditions of use, while the radial openings 66 formed in the rotatable cam shaft are sufficiently
 20 in number to provide adequate means for feeding oil into the interior of the shaft from the conduit 60 through the opening 67 formed therein.

While I have shown and described in considerable detail a specific embodiment of my invention, it is to be understood that this showing and description is illustrative only, and for the purpose of rendering my invention more clear, and that I do not regard
 25 the invention as limited to the details of construction illustrated or described, nor any of them, except in so far as I have included such limitations within the terms of the following claims, in which it is my
 30 intention to claim all novelty inherent in my invention broadly as well as specifically.

What I claim as new and desire to secure by Letters Patent is:

1. In a lubricating system for internal combustion engines, a hollow cam shaft, hollow bearing shafts positioned upon opposite sides of the cam shaft, a conduit positioned at one end of the engine extending transversely of said shafts and communicating
 40 with the interior of each shaft, and an oil supply pipe communicating with the conduit.
 45

2. In a lubricating system for lubricating the valve operating mechanism of an in-

ternal combustion engine of the V-type, a 50 hollow cam shaft, hollow bearing shafts upon opposite sides of the hollow cam shaft, a conduit extending transversely of the engine at one end thereof and having parts 55 communicating with the interior of the hollow shafts, and an oil supply pipe communicating with the conduit to supply lubricant thereto.

3. In a lubricating system, a hollow cam shaft, a plurality of hollow bearing shafts 60 positioned upon opposite sides of the cam shaft, a conduit extending transversely of the several shafts and positioned above the horizontal plane of some of the shafts, and below the horizontal plane of others of the 65 shafts, and communicating with the interior of each of the hollow shafts, and an oil supply pipe communicating with the conduit.

4. In a lubricating system for engines, a plurality of substantially parallel hollow 70 shafts, a conduit extending across one end of the engine and having ports located adjacent the ends of the parallel shafts, ports formed in the ends of the hollow shafts and adapted to register with the ports in the 75 conduit for admitting lubricant to the hollow shafts, said conduit being positioned above the horizontal plane of some of the shafts and below the horizontal plane of the other shafts, and an oil supply pipe 80 communicating with the conduit.

5. In a lubricating system for engines, a plurality of substantially parallel hollow shafts, a conduit extending across one end of the engine and having ports located adjacent to the ends of said parallel shafts, certain of said ports being directed upwardly and the other ports being directed downwardly, ports formed in the ends of the hollow shafts and adapted to register 90 with the ports in the conduit for admitting lubricant to the hollow shafts, and an oil supply pipe communicating with the conduit.

In testimony whereof, I affix my signature.

GARNET C. BROWN.
